CLAIM

The ornamental design for a charger for walkie-talkie, as shown and described.

DESCRIPTION

FIG. 1 is a front elevational view of a charger for walkie-talkie showing of my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof; and,

FIG. 7 is a top, front, right side perspective view thereof. The broken lines depict portions of the charger for walkie-talkie that form no part of the claimed design.
